J. M. MOORE & F. F. KAMP, JR.
 SAFETY STOP SIGNAL ATTACHMENT FOR RAILWAY SIGNALS.
 APPLICATION FILED MAY 18, 1908.

913,536.

Patented Feb. 23, 1909.

UNITED STATES PATENT OFFICE.

JOHN M. MOORE, OF BRIDGEVILLE, AND FRANK F. KAMP, JR., OF LAWRENCE, PENNSYLVANIA.

SAFETY-STOP-SIGNAL ATTACHMENT FOR RAILWAY-SIGNALS.

No. 913,536.

Specification of Letters Patent.

Patented Feb. 28, 1909.

Application filed May 18, 1908. Serial No. 433,373.

To all whom it may concern:

Be it known that we, JOHN M. MOORE and FRANK F. KAMP, Jr., citizens of the United States of America, residing at (1) Bridgeville, (2) Lawrence, in the county of (1) Allegheny, (2) Washington, and State of Pennsylvania, have invented certain new and useful Improvements in Safety-Stop-Signal Attachments for Railway - Signals, 10 of which the following is a specification, reference being had therein to the accompanying drawing.

This invention relates to a safety stop signal attachment for railways, and the 15 primary object of our invention is to prevent accidents by trains running past signals when set at danger.

Another object of our invention is to locate the safety stop signal a prescribed distance 20 back from the switch point, draw-bridge, railroad crossing, or in fact any place where it would require a train to be stopped, thereby preventing accidents, the destruction of property and in all probability the loss of 25 life.

A further object of our invention is the provision of novel means for automatically applying air-brakes of a train through the intermediary of a semaphore signal.

30 The present invention is an improvement on the device shown and claimed in Letters Patent No. 870,453, granted to us November 5th, 1907, and aims to provide means for insuring the return of the brake valve actuating rod to its proper position after each 35 actuation thereof, as well as insuring the actuating rod normally maintaining its proper position for actuation by the track device.

40 In the drawings, Figure 1 is a vertical section of a signal post with our improvement shown in elevation. Fig. 2 is an elevation on a large scale of the engineer's brake valve and parts appurtenant thereto. Fig. 3 is an 45 elevation partly in section of the brake operating mechanism, Fig. 4 is a bottom plan of the brake valve shaft. Fig. 5 is a view in perspective on an enlarged scale of the guide brake operating slide. Fig. 6 is a similar 50 view of the slide for operating the brake valve, and Fig. 7 is a top plan view of the brake valve operating means.

The reference numeral 1 designates a hollow post or tower upon which a semaphore 55 arm 2 is pivotally secured, the usual electric motor 3 being arranged at the top of the post

to operate the arm 2. At the base of the hollow post 1 is a suitably fulcrumed bell-crank lever 4 connected by a rigid connection 5 to the semaphore arm, and by a link 6 to a slide 7 of inverted T shape.

The slide 7 is movably supported within a guide 8 corresponding in contour to the slide, and secured upon a support 9 at one side of the track 10. The slide 7 is provided on its free end with a bevelled lug adapted to be struck by the lug 12 formed upon a disk 13 mounted upon the lower end of a vertical shaft 14 supported in bearings 15 and 15^a, carried by the locomotive. The disk 13 is 70 guided between parallel guide-plates 16 fixed upon the shaft 14, said guide plates having flared edges to permit of the lug 11 easily moving between said guide plates. Upon the upper end of the shaft 14 is mounted a disk 17, formed with a lug 18, adapted to engage a corresponding lug 19 formed upon a disk 20, mounted upon the stem 21 of the engineer's brake-valve 22.

Arranged between the disk 17 and the bearing 15^a is a coil spring 25, said spring being employed to retain the shaft 14 in its normal position, and also to return same to its normal position after each actuation.

The utility and operation of the mechanism constructed as above described will be readily understood.

When the semaphore arm 2 is set to indicate danger, the slide 7 is projected towards the track 10, bringing its lug 11 into position 90 to be struck by the lug 12 of the disk 13, so that if the danger signal is not observed by the engineer, the shaft 14 will be turned automatically to operate the brake-valve 22 and set the brakes. The usual lever 23 is 95 fixed upon the upper end of the brake valve stem 21 to be manipulated by the engineer.

Our improved railway safety device is applicable to any automatic or mechanically operated signal that is employed to stop a 100 train. The device is adapted to operate independently of an engineer of a locomotive and is adapted to prevent rear end collisions when used in connection with electric or minute blocks of any kind of signal or semaphore.

Having now described our invention what we claim as new, is:—

The combination with a signal post and a semaphore arm pivotally secured thereto, of a bell-crank lever fulcrumed at the base of 110 the post, a rigid connection between said

arm and said bell-crank lever, a horizontally guided slide connected to said bell-crank lever, a beveled lug carried by said slide, and means carried upon a locomotive and adapted 5 to contact with said beveled lug and operate a brake valve upon the locomotive, comprising a vertical shaft, a disk on the lower end of said shaft and having a lug, interlocking shoulder disks each having a lug and 10 mounted one upon the upper end of said shaft and the other upon the stem of said brake valve, and a retracting spring ar-

ranged on the vertical shaft at the upper end thereof for returning said shaft to its normal position for each actuation thereof, substantially as and for the purpose herein set forth. 15

In testimony whereof we affix our signatures in the presence of two witnesses.

JOHN M. MOORE,
FRANK F. KAMP, JR.
